UNITED STATES PATENT OFFICE.

CHARLES T. WADE, OF ANNAPOLIS, MARYLAND.

GAS-ENGINE.

1,040,472.

Specification of Letters Patent.

Patented Oct. 8, 1912.

Application filed September 1, 1910. Serial No. 580,073.

To all whom it may concern:

Be it known that I, CHARLES T. WADE, a citizen of the United States, at present stationed at Annapolis, in the county of Anne Arundel and State of Maryland, have invented certain new and useful Improvements in Gas-Engines; and I do hereby declare the following to be a full, clear, and exact description of the invention, such as will enable others skilled in the art to which it appertains to make and use the same.

My invention relates to improvements in gas engines and the object of my invention is to provide a plurality of explosion cylinders arranged in a straight line, with a single compression cylinder between two explosion cylinders, and all of the pistons being mounted on a single piston rod, which is provided with means for admitting charges of carbureted air from the compression cylinder into the explosion cylinders alternately at the proper times.

A further object of the invention is to provide efficient means for cooling the interior of the explosion cylinders, which, as is well known, is a matter of great difficulty.

Cross reference is made to a prior application, Serial No. 491039, filed by applicant on Apr. 20, 1909, for a gas engine construction not covered by the claims in this application.

With these objects in view, and others that will appear in the detailed description, my invention consists in the construction and combinations of parts as hereinafter described and claimed.

In the accompanying drawings:—Figure 1 is a vertical section of my improved gas engine, partly in elevation. Fig. 2 is a cross section on the line 2—2 of Fig. 1. Fig. 3 is a cross section on the line 3—3 of Fig. 1. Fig. 4 is a cross section through the piston rod and the top of one of the explosion cylinders. Figs. 2, 3 and 4 are on a larger scale than Fig. 1.

My invention is a double acting two cycle engine and can be arranged in a vertical plane as shown in the drawing, or in a horizontal plane or an inclined plane as desired. Fig. 1 represents a fly wheel mounted on the shaft *b* located in bearings on the base *c*. This shaft is provided with a crank *10* which is connected by means of the common connecting rod *d* with a wrist-pin *11* carried by the piston *e* in the explosion chamber next to

the base *c*, said piston being provided with the usual packing rings *f*.

The explosion cylinder *g* is bolted on to the base *c* in the usual manner and is provided with a series of narrow exhaust ports *h*, extending at intervals completely around the periphery of the cylinder. It is provided with the usual water jacket *i*, although it may be air cooled if desired. Bolted to one end of the cylinder *g* is the compression cylinder *j*, which has bolted to its other end the second explosion cylinder *k*. This second explosion cylinder is also provided with a series of narrow exhaust ports *l*, extending at intervals completely around the periphery of the cylinder. *m* is a water jacket mounted on this cylinder, which however may be air cooled if desired. The compression cylinder *j* is slightly larger in diameter than the explosion cylinders in order to give a greater space for drawing in charges of carbureted air. The explosion cylinders *g* and *k* are each open at one end and are provided, at the other end with heads *n* and *o* respectively, which heads form partitions between said cylinders and the compression cylinder *j*. These partitions form bearings for the piston rod *p*, and in these partitions are mounted packing rings *q* and *r*. Mounted on the piston rod *p* and located within the cylinder *j* is the compression piston *u* and near this piston and on both sides of the same slits 4 and 5 are cut in the rod *p*, which will be hereinafter described. The piston rod at one end is screwed into a screw threaded opening in the piston *e*, located in one of the explosion cylinders, and on its other end is screwed a piston *v* located in the other explosion cylinder. These three pistons are screwed to the piston rod *p* at equal distances apart, and are each provided with the usual packing rings.

w and *x* represents spark plugs for the explosion cylinders, but obviously any well known means of ignition may be used.

Mounted on the cylinder *j*, at one side, is a T shaped pipe *3* the ends of which are screwed into openings into the cylinder *j*. Near the ends of this pipe are located the check valves 1 and 2 and the pipe 3 communicates with the cylinder *j* near the ends of said cylinder. These check valves prevent backward flow when the charges of carbureted air are being compressed first on one side and then on the other side of the

piston u . Connected to the T shaped pipe 3 is a carbureter 12 of any approved construction, or a pipe leading to a gas producer.

In Figs. 3 and 4 is shown on an enlarged scale means for delivering the compressed charge from the compression cylinder to the explosion cylinder consisting of a number of slits such as 5 cut in the circumference of the piston rod p near the point where it is joined to the piston u . As shown in Fig. 3, these slits do not pass entirely through the wall of the piston rod. The piston rod p is hollow from end to end as shown and the three pistons are, of course, centrally cut away at the point of junction with the piston rod. I prefer to make the piston rod of considerable size relatively to the pistons. Connected to the top of the cylinder k is a casing 9 which is connected to a suction fan 8 of any desired type, said fan being driven from any suitable source of power by a pulley 7. The purpose of this fan is to cause a constant circulation of cooling fluid through the hollow piston rod p . The crank casing being open the suction fan 8 causes a constant current of air, as indicated by the arrows, through the bottom part of the engine and up through the hollow piston rod p . The piston rod is made, as already described, comparatively large in diameter and with comparatively thin metal walls, the cylindrical shape affording sufficient strength, and the cooling action is therefore very rapid.

As is well known, the chief difficulties of operating internal combustion engines of large size are (a) to overcome momentum of reciprocating parts; (b) to cool the engine; (c) to keep valves tight and passages clear. In this engine (a) is taken care of by having a compression at the end of each stroke; (b) by cooling surfaces, external and internal, which combined area may be varied for a given effective piston area; and (c) by providing enough gas under pressure in the compression chamber to fill the entire combustion chamber, and having only mechanical openings, not valves, subject to the heat of the combustion chamber.

The operation is as follows: Supposing that the parts are in the position shown in Fig. 1 with a compressed charge in the cylinder g . This charge being ignited forces the piston e down, and by means of the piston rod p the piston u is drawn down at the same time compressing a charge of carbureted air on the lower side of the piston u in the compression chamber. This compression continues until the piston u has about reached the lowest limit of its stroke, when the exhaust ports h are uncovered, releasing the pressure in the cylinder g , and immediately after the slits 5 form a communication between the cylinders j and g admit-

ting a charge of carbureted air in the top of the cylinder g , the slits 5 being longer than the cylinder head. This completely blows out the burnt charge from the cylinder g . At the approximate beginning of the return stroke ignition of the compressed charge in the cylinder k , as hereinafter described, takes place, and upon the upstroke the piston e then compresses a charge of the carbureted air in the upper part of the cylinder g , while the piston u is drawing in a new supply of carbureted air on its lower side through the valve 2, and on its upper side compressing a charge of carbureted air which had previously been drawn in through the check valve 1. Upon reaching the limit of the upward stroke the exhaust ports l are uncovered, releasing the pressure in the cylinder k and immediately after the slits 4 above the piston u will reach the position shown in Fig. 1 and a compressed charge of carbureted air is admitted into the upper explosion cylinder k . This completely blows out the burnt charge in the cylinder k . The downward movement of the piston v in the cylinder k compresses the charge of carbureted air in this cylinder until it reaches the lowest limit of the stroke, when the charge is ignited, the operation being continued indefinitely, with explosions taking place in the cylinders g and k alternately, thus driving the shaft b and fly wheel a . During all this time the fan 8 is drawing a supply of cooling fluid through the piston rod p and the cylinders g and k are being cooled by a water jacket or in any suitable manner. The walls of the piston rod being of thin metal and said rods being connected directly to the three pistons, these pistons and the rod are thus efficiently cooled.

I do not limit myself to the kind of cooling fluid drawn in through the hollow pipe p as this might be water, air or steam at low pressure.

While I have thus described my invention I wish it to be distinctly understood that I do not limit myself to the exact details shown and described, as these could be varied considerably without departing from the scope of my invention, the main feature of which is to provide two explosion cylinders with a compression cylinder between them, all three located in the same straight line and with a piston rod of such a construction that the charges of carbureted air are admitted from the compression cylinder into the explosion cylinders alternately, without the use of valves, and a supply of cooling fluid is continuously drawn through the hollow piston rod.

I claim:

1. In a gas engine, the combination of coaxially arranged compression and explosion cylinders, pistons in said cylinders, a hollow piston rod secured to said pistons and ter-

- minating at the outer face of said explosion piston in an open end communicating with the explosion cylinder, said piston rod being provided with means for establishing communication between said compression and explosion cylinders, and means for directing a current of cooling air through said hollow piston rod and the communicating explosion cylinder.
- 10 2. In a gas engine, the combination of a compression cylinder, explosion cylinders supported co-axially on the respective heads of said compression cylinder and provided with open outer ends, pistons in said cylinders, a hollow piston rod secured to said several pistons and terminating in open ends at the outer faces of said explosion pistons, said piston rod being provided with means for establishing communication between said compression and explosion cylinders, and means for directing a current of cooling air through said hollow piston rod.
- 15 20
3. In a gas engine, the combination of a compression cylinder, explosion cylinders supported co-axially on the respective heads of said compression cylinder and provided with open outer ends, pistons in said cylinders, a hollow piston rod secured to said several pistons and terminating in open ends at the outer faces of said explosion pistons, 25 said piston rod being provided with means for establishing communication between said compression and explosion cylinders, a casing extending from the open end of one of said explosion cylinders, and a fan in 30 said casing for directing the current of cooling air through said hollow piston rod.
- In testimony whereof, I affix my signature, in presence of two witnesses.

C. T. WADE.
